W. W. WILSON.

UNDERREAMER.

APPLICATION FILED APR. 23, 1917.

1,279,814.

Patented Sept. 24, 1918

INVENTOR,

William W. Wilson,
by Raymond J. Kuhne,
HIS ATTORNEY.

UNITED STATES PATENT OFFICE.

WILLIAM W. WILSON, OF LOS ANGELES, CALIFORNIA.

UNDERREAMER.

1,279,814.

Specification of Letters Patent. Patented Sept. 24, 1918.

Application filed April 23, 1917. Serial No. 163,877.

To all whom it may concern:

Be it known that I, WILLIAM W. WILSON, a citizen of the United States, residing at Los Angeles, in the county of Los Angeles and State of California, have invented new and useful Improvements in Underreamers, of which the following is a specification.

This invention relates to underreamers for enlarging oil well holes to permit the lowering of casing which is used for protecting the hole and preventing invasion thereof by water and other fluids. Such underreamers are employed to ream away the circular formation beneath the casing which remains after the drilling operation has produced the hole to a point beneath the lowermost section of the casing. Such underreamers in ordinary practice comprise in the main a hollow or chambered body within which are disposed means for expanding and permitting collapsing of cutters or bits, which cooperate with the body or means thereon in such collapsing and expanding actions. Specifically such means within the chamber in the body in the best practice comprise a rod within the lower or outer end of which the cutters are connected or from which the cutters are suspended, a coil spring surrounding such rod and acting upon the same to force the cutters into expanded positions. The means for assembling together such spring and rod and body and cutters may comprise a suitable shoulder on the body itself, or, in accordance with better practice, as exemplified in Letters Patent previously issued to me upon application of Elihu C. Wilson, No. 1,183,151, under date of May 16, 1916, such means comprise a device passed through an elongated slot in the rod, and seated at its ends in slots or openings in the tubular or chambered body. In accordance with this combination of parts and features the coil spring rests directly upon such device instead of upon the shoulder in the body mentioned; and the spring-actuated rod and its spring may be introduced within the chamber or bore in the body at the lower open end thereof, instead of being intro-

duced within said chamber at the upper end thereof, which necessitates the provision of a joint in the body to permit access to such chamber at its top. This assembling of the underreamer at the bottom or lower end is of extreme convenience and advantage in many respects, inasmuch as the parts have frequently to be disassembled in order to remove the cutters or bits for sharpening or dressing. This cannot be done where the jointed body is used without so unjointing the body, which has many disadvantages, taking more time and introducing the factor of risk incident to a further joint in the string of tools including the underreamer.

In accordance with the present invention, I provide a device for so assembling together the parts and features mentioned, which likewise is introduced within the elongated slot in the spring-actuated rod and furnishes a support for the spring, and is seated at its ends in slots or openings in the tubular body. This device, however, comprises a plurality of members, disposed one above the other beneath the spring, and provided with or including means for holding both members in positions of service. In the device of the patent of May 16, 1916, mentioned, only a single part was so disposed beneath the spring, and it was specifically held in place by the spring, and the openings or slots in the body were of necessity of greater depth or were enlarged, so that the key or cutter device could be introduced, with its lower wing or extension, and such extension could be passed downwardly into the bore and serve to prevent endwise movement of the unitary device and thereby hold such device against displacement from the body.

In accordance with the present invention, the assembling device or spring stop means may be formed to fill the complete depth of the openings or slots in the walls of the body, when assembled together and in positions of service, and the pressure of the spring is not relied upon to prevent endwise movement of the device in either direction or to hold such device in place. One member is pro-

vided with a wing or projection received within the bore in the body and preventing endwise movement of such member, and the other member co-acts with the first named 5 member to hold the same in position and is likewise provided with means for preventing endwise movement of said second member.

The invention has for its object to provide an improved combination of underreamer 10 parts, members and features which will be superior in point of relative simplicity and inexpensiveness of construction and organization in the respects mentioned, of increased convenience and facility in the use, and 15 which will likewise be superior in point of durability and positiveness and efficiency in action and service.

With the above and other objects in view, the invention consists in the novel and useful 20 provision, formation, combination, association, inter-relation, and relative arrangement of parts, members and features, all as hereinafter described, shown in the drawing, and finally pointed out in claims.

25 Figure 1 is an elevation of an improved underreamer constructed and organized to embody the invention, parts being broken away and sectioned for fullness of illustration, and the cutters or bits being shown in 30 expanded positions;

Fig. 2 is a view similar to Fig. 1, the cutters or bits being shown in contracted positions;

Fig. 3 is a transverse detail sectional view 35 taken upon the line x^3-x^4 , Fig. 1, and looking in the direction of the appended arrows; and

Fig. 4 is a detail vertical sectional view 40 of the same, taken in a plane at right angles to that of the showings in Figs. 1 and 2, upon the line x^4-x^4 , Fig. 3, and looking in the direction of the appended arrows.

Corresponding parts in all the figures are 45 designated by the same reference characters.

Referring with particularity to the drawing, and bearing in mind the general description of the invention hereinbefore made, A designates an underreamer body provided with an internal chamber or bore 50 α within which is mounted an elongated rod 5 free to play lengthwise therein excepting as constrained by a coil compression spring 6, one end of which bears upon an adjustable nut 7 at the upper end of said rod 5 and the other end of which is seated upon the assembling means B which particularly embody the invention, and which are introduced into positions of service through transverse slots 8 in the reamer body and an 55 elongated slot 9 in the rod 5. Cutters C and D are pivotally connected with an enlarged head 10 upon the lower end of the rod 5, as at 5^a, and which is disposed, in the specific form shown in the drawing, in an open

mouth 11 at the lower end of the reamer 60 body and communicating with the bore or chamber α in the body. Such cutters suitably coöperate with the sides of the open mouth 11 and with lugs 12 projecting downwardly from the lower terminal portion of 70 said mouth, to produce the expansion and collapse of the cutters indicated in the drawing. This cutter mounting and action is not concerned in the issues of the present invention.

The assembling means B comprise two members, b and c , each of which comprises an elongated key, 13 and 14 respectively, the key 13 being introduced within the slots 8 and 9 above the key 14, and the latter having a downwardly ranging wing or extension 15 received within the bore α and preventing endwise movement of the member 14. The co-engaging edges of said keys 13 and 14 lie in a plane ranging at right angles 80 to the longitudinal axis of the reamer body, so that there is no tendency of either member 13 or 14 to produce a wedge action upon the other tending to displace the same. The free key or member 13 is shown specifically 90 as prevented from endwise movement in one direction by means of a downwardly ranging head or offset 16 received within a notch or recess 17 in the upper portion of the key or member 14; and is prevented from endwise movement in the opposite direction by a cotter pin or the like 17' which is passed through the opposite end of the key or member 13 and received within a recess 18 in the body A at the end of the respective body 100 slot 8.

The key 14 is first introduced into the position shown in the drawing, whereupon the key 13 is then slid in above it until the offset 16 enters the notch 17, whereupon the 105 cotter pin 17' is passed through the eye 17^a in the key 13. When in such positions both keys substantially fill the slots 8, and both keys are prevented from displacement until the cotter pin 17' is withdrawn, in such position such keys assembling together the body A, the spring 6, the rod 5 and the cutters C and D. In order to disassemble the parts and features mentioned, it is only necessary to withdraw the cotter pin 17' and drive out the key 13 endwise in a direction which removes the offset 16 from the notch 17. The key 14 may then be wedged up and removed from the slots 8 and 9 in either direction, endwise. In putting the keys into 110 position, a suitable wedge or tool may be employed, pilot fashion, to be driven through the slots 8 and 9 under the spring, in wedge action to raise the spring and permit the keys 14 and 13 to follow the same and be 115 brought into position shown in the drawing, the key 14 being entered first and its wing or projection 15 slid down into the bore in

the body, whereupon the key 13 is entered over the key 14 and secured in position.

Having thus disclosed my invention; I claim and desire to secure by Letters Patent:

1. In an underreamer, the combination, with a body having an interior chamber, a slotted spring-actuated rod in said chamber, and cutters connected with said rod and adapted to coöperate with said body in expansion and collapsion; of means for assembling together said body and spring-actuated rod and cutters comprising a plurality of members adapted to be received one above the other within the slot in said rod and to be seated at their ends in registering slots in said body; each of said members being provided with means for preventing endwise movement thereof in either direction.
2. In an underreamer, the combination, with a body having an interior chamber, a slotted spring-actuated rod in said chamber, and cutters connected with said rod and adapted to coöperate with said body in expansion and collapsion; of means for assembling together said body and spring-actuated rod and cutters comprising a plurality of members adapted to be received one above the other within the slot in said rod and to be seated at their ends in registering slots in said body; each of said members being provided with means for preventing endwise movement thereof in either direction; and said members being inter-engaged to prevent movement of one thereof in one direction.
3. In an underreamer, the combination, with a body having an interior chamber, a slotted spring-actuated rod in said chamber, and cutters connected with said rod and adapted to coöperate with said body in expansion and collapsion; of means for assembling together said body and spring-actuated rod and cutters comprising a plurality of members adapted to be received one above the other within the slot in said rod and to be seated at their ends in registering slots in said body; one of said members being provided with a projection received within the chamber of the body and preventing movement of said member in either direction; and the other of said members being provided with means for preventing movement thereof in either direction.
4. In an underreamer, the combination, with a body having an interior chamber, a slotted spring-actuated rod in said chamber and cutters connected with said rod and adapted to coöperate with said body in expansion and collapsion; of means for assembling together said body and spring-actuated rod and cutters comprising a plurality of members adapted to be received one above the other within the slot in said rod and to be seated at their ends in registering slots in said body; one of said members be-

ing provided with a projection received within the chamber of the body and preventing movement of said member in either direction; and the other of said members being provided with means for preventing movement thereof in either direction; which said latter means are separate and one of which is detachable.

5. In an underreamer, the combination, with a body having an interior chamber, a slotted spring-actuated rod in said chamber and cutters connected with said rod and adapted to coöperate with said body in expansion and collapsion; of means for assembling together said body and spring-actuated rod and cutters comprising a plurality of members adapted to be received one above the other within the slot in said rod and to be seated at their ends in registering slots in said body; one of said members being provided with a projection received within the chamber of the body and preventing movement of said member in either direction; and the other of said members being provided with means for preventing movement thereof in either direction; said members having contacting edge portions extending at right angles to the longitudinal axis of the body.

6. In an underreamer, the combination, with a body having an interior chamber, a slotted spring-actuated rod in said chamber and cutters connected with said rod and adapted to coöperate with said body in expansion and collapsion; of means for assembling together said body and spring-actuated rod and cutters comprising a plurality of members adapted to be received one above the other within the slot in said rod and to be seated at their ends in registering slots in said body; each of said members being provided with means for preventing endwise movement thereof in either direction; said members jointly coöperating to prevent displacement of either of the same from said slots.

7. In an underreamer, the combination, with a body having an interior chamber, a slotted spring-actuated rod in said chamber, and cutters connected with said rod and output to coöperate with said body in expansion and collapsion; of means for assembling together said body and spring-actuated rod, and cutters comprising a plurality of members adapted to be received within the slot in said rod and to be seated at their ends in registering slots in said body; each of said members being provided with means for preventing endwise movement thereof in either direction.

8. In an underreamer, the combination, with a body having an interior chamber, a slotted spring-actuated rod in said chamber, and cutters connected with said rod and

adapted to coöperate with said body in expansion and collapsion; of means for assembling together said body and spring-actuated rod and cutters comprising a plurality of members all the edges of which are in the main parallel, said members being adapted to be received one above the other within the slot in said rod, and to be seated at their ends in registering slots in said body; each of said members being provided

with means for preventing endwise movement thereof in either direction.

In testimony whereof, I have signed my name to this specification in the presence of two subscribing witnesses.

WILLIAM W. WILSON.
